[57] CLAIM

The ornamental design for a domestic appliance for
grating, slivering and slicing, substantially as shown.

DESCRIPTION

FIG. 1 is a top front perspective view of a domestic
appliance for grating, slivering, and slicing showing the
grating and slivering portion of my new design;

FIG. 2 is a top rear perspective view thereof;

FIG. 3 is a left side perspective view thereof;

FIG. 4 is a right side perspective view thereof;

FIG. 5 is a top perspective view thereof;

FIG. 6 is a bottom perspective view thereof;

FIG. 7 is a perspective view of the top, front, and right
side thereof;

FIG. 8 is a perspective view of the bottom, front and
left side thereof;

FIG. 9 is a perspective view similar to FIG. 8, the
thumb piece being partially withdrawn from the casing;

FIG. 10 is a front perspective view thereof in an open
condition for slicing;

FIG. 11 is a right side perspective view of FIG. 10;

FIG. 12 is a left side perspective view of FIG. 10; and

FIG. 13 is a perspective view of the top, front, and left
side of FIG. 10.
